LOUIS E. RUEHLMANN, OF PHILADELPHIA, PENNSYLVANIA, ASSIGNOR TO HALE & KILBURN CORPORATION, OF PHILADELPHIA, PENNSYLVANIA, A CORPORATION OF DELAWARE.

PANEL-RETAINING MEANS.

1,312,925.

Specification of Letters Patent. Patented Aug. 12, 1919.

Application filed November 9, 1917. Serial No. 201,156.

To all whom it may concern:

Be it known that I, LOUIS E. RUEHLMANN, a citizen of the United States, residing at Philadelphia, in the county of Philadelphia and State of Pennsylvania, have invented 55 certain new and useful Improvements in Panel-Retaining Means, of which the following is a specification.

My invention relates to a construction intended to hold the glass or other panels in 10 position in framed structures, such as doors, sashes, transoms and the like, in such manner that the panel may be quickly positioned or removed without the necessity of using 15 or removing screws or the like. More particularly, the invention is devised to provide means for retaining glass panels in the doors of railway cars, etc. If the glass should break at any time during the operation 20 of the car, the glass may be quickly removed, by my invention, and a new panel substituted at any point on the road, without removing a considerable number of screws, which is ordinarily necessary and 25 involves considerable delay.

My invention attains this end by the provision of a number of retaining strips which are inserted within flanges or abutments on the frame of the door, these strips overlapping 30 the edge portion of the panel and holding the same in position. The strips fit together at their ends so as to hold each other in position, as by having the top horizontal strip mounted with its ends resting on the 35 tops of the two vertical strips and the bottom strip fitting between the lower ends of the vertical strips. When the panel is to be removed, the strips are slid or forced out of position, which, in the case just referred to, 40 would require the bottom strip to first be raised above the edge of the coating flange or abutment on the frame member and afterward the vertical strips and top strip similarly slid out of position. To aid in removing 45 the strips, the latter are provided with openings therein, or shoulders thereon, or the like, which may be pressed against by a screw-driver or other instrument to force the strips out of position.

50 In order that a clearer understanding of my invention may be had, attention is hereby directed to the accompanying drawings forming part of this application and illustrating certain embodiments of my inven-

tion. In the drawings, Figure 1 represents 55 a front elevation of a door equipped with my invention, Fig. 2 is an enlarged front elevation of a glass panel in the door with adjacent parts, partly broken away and partly shown in section, and Fig. 3 is an 60 enlarged sectional view taken on line 3—3 of Fig. 1.

Referring to the drawings, the door 1 is illustrated as provided with one or more glass panels, such as that shown at 2, and 65 the usual rails 3, 4 and 5, stiles 6 and 7 and the vertical frame member 8 separating the two upper glass panels. The door illustrated is formed of steel in which the different parts are pressed to shape, although 70 the invention may obviously be applied to wooden or other doors. The frame members surrounding the opening for a glass panel may all be of the same construction and are illustrated sufficiently by the section taken 75 through a stile, as shown in Fig. 3.

As there illustrated, the stile or other frame member 7 may be of usual construction and is shown as having a flange 9 at its inner edge, which is bent inwardly of the 80 opening for the panel, as shown at 10, and thence bent back at 11, parallel to flange 10, around a flange 12, which extends inwardly of the opening from the flange 13, which, together with the flange 9, forms the inner 85 edge of the frame member. Flanges 10, 11 and 12 may be positioned midway of the depth of the frame member 7, or at any other convenient point, and form what may 90 be termed a rear abutment or flange.

A forward inwardly directed flange or abutment must also be provided to extend inwardly of the opening a less distance than the rear abutment, as is illustrated at 14. This may readily be accomplished by providing a steel channel member 15, which is secured to the edge flange 9 of each frame member, with its forward flange 14 preferably in alinement with the front surface of frame member 7, and its rear flange 16 contacting against the flange 10 of the rear abutment. The glass pane 2 is illustrated as having the usual rubber channel 17 cemented to the edge of the glass to provide a proper seat for the glass. The forward 105 flanges or abutments 14 are sufficiently short to enable the glass panels, together with their rubber channels 17, to be pushed past the

inner edges of the same to mount the panel with its rear surface, adjacent its edges, contacting against the inner portions of flange 10 of the rear abutment, as shown.

5 It will be observed that a space is left between the edges of the glass panel and the inner surfaces of the frame members surrounding the opening. This space may be filled by wooden filler strips 18, or equivalent construction, the inner surfaces of which provide seats against which the edges of the glass panel contact. The front surfaces of the fillers 18 also act as abutments or frictional engaging means for the glass retaining strips, as will be described.

10 The retaining strips, in the case of a rectangular panel, as illustrated, comprise a pair of vertical strips 19, 19, a top horizontal strip 20 and a bottom horizontal strip 21. Each strip is inserted between a forward flange or abutment 14 and the filler 18, the retaining strip being sufficiently wide to extend beyond the forward abutment 14 and overlap and press against the front surface 25 of the glass panel, considering the rubber channel 17 as part of the glass panel. The front abutment 14 of the frame member may be bent back upon itself, as illustrated, for the sake of stiffness. The dimensions of the 30 parts are so chosen that each retaining strip will fit into the space between the forward abutment and the filling strip 18 with a forced fit, and will press against the front surface of the panel sufficiently to clamp 35 the panel between the strip and the rear abutment 10. The filling strip 18 provides a bearing or abutment for the retaining strip, as stated, to hold the retaining strip in alinement with the panel, but it is obvious 40 that equivalent means may be used for this purpose.

Means should be provided upon each retaining strip, so that the same may be engaged by a suitable instrument and forced 45 out of position. Suitable shoulders or abutments for this purpose may be provided by forming slots 22 in the retaining strips, these slots being a slight distance beyond the inner edges of the forward abutments 14 inwardly of the opening for the panel. It is, 50 therefore, obvious that the point of a screw-driver or the like may be inserted in the slots 22 and pressure exerted on the screw-driver, as by pivoting the same about the inner edge 55 of abutment 14, to push the retaining strips inwardly of the opening out of engagement with the forward abutments and filling strips 18.

60 In order that the retaining strips may be positively held in position, it is desirable to mount the top strip 20 with its end portions resting on the tops of the vertical strips 19, and the bottom strip 21 with its ends fitting between the bottom portions of the vertical 65 strips 19. In mounting the strips in posi-

tion, it is, therefore, necessary to first insert the top horizontal strip 20, and then the two vertical strips and lastly the bottom strip 21. Strip 20 is prevented from falling out by strips 19, and the latter are held in position by strip 21. Strip 21 is held in position by gravity and also by friction with the adjoining members. Preferably, the top strip 20 and vertical strips 19 are beveled at their meeting ends, as shown, so that strip 20 will hold strips 19 in position at the top, as well as strips 19 holding strip 20 in position. Therefore, to mount strips 19 in position, their upper beveled ends are first inserted under the beveled ends of strip 20, and strips 19 then swung around into the vertical position, which may be aided by rounding the bottom ends of strips 19 as shown.

70 When it is desired to remove a panel and to insert a new one, as in case of breakage of the glass, the bottom strip 21 must first be removed by driving the same upwardly until it is clear of the front abutment of the adjacent frame member 4, after which the vertical strips 19 are forced laterally inwardly of the opening and removed, after 75 which the top strip 20 may be similarly forced downwardly and removed.

80 It is obvious that the retaining strips might be positioned between the rear surface of the panel and the rear abutment as well as between the front surface of the glass and the forward abutment. For convenience, the abutments or flanges engaged by the retaining strips will be referred to in the claims 85 as the forward abutments or flanges. It is also obvious that my invention is not limited to the exact details of construction described and illustrated, but that reasonable equivalents of the same are included within 90 the scope of the invention, as shown by the 95 accompanying claims.

100 What I claim is:—

1. The combination of a frame surrounding a rectangular opening, having forward and rear inwardly directed abutments about the opening, the inner portion of the rear abutments being adapted to be contacted by the rear edge portions of a glass panel and the forward abutments being shorter in 110 length than the rear abutments, fillers positioned between the forward and rear abutments and the edge of a glass panel, and removable retaining strips each positioned between the forward abutment and filler on one side so as to extend inwardly beyond the abutment to overlap and press upon the front of a glass panel, the top horizontal strip having its ends rest on the two vertical strips and the bottom horizontal strip 115 and having squared ends fitting between the lower end portions of the vertical strips, said strips having abutment means whereby the same may be engaged by an instrument 120 and slid out of glass-retaining position. 125 130

2. The combination of a frame surrounding a rectangular vertical opening, having forward and rear inwardly directed abutments about the opening, and seats for the 5 edge of a panel between the abutments, the rear abutments extending inwardly of the opening beyond the seats and beyond the inner edges of the forward abutments, and removable retaining strips inserted between 10 said seats and forward abutments so as to extend beyond the inner edges of said abutments to overlap and contact against the front edge portions of a panel when the latter is positioned against said seats with 15 its rear edge portions against the rear abut-

ments, the top horizontal strip having its ends rest on the two vertical strips and the bottom horizontal strip having squared ends fitting between the lower end portions of the vertical strips, said strips having openings 20 therein adapted to be engaged by an instrument so that the strips may be slid out of position.

This specification signed and witnessed this 7th day of November, 1917.

LOUIS E. RUEHLMANN.
